UNITED STATES PATENT OFFICE.

JOHN HENRY RICHARDSON, OF SAN PEDRO, CALIFORNIA.

SAFETY-PIN.

1,310,929.

Specification of Letters Patent. Patented July 22, 1919.

Application filed December 28, 1918. Serial No. 268,683.

To all whom it may concern:

Be it known that I, JOHN H. RICHARDSON, a citizen of the United States, and a resident of San Pedro, in the county of Los Angeles and State of California, have invented certain new and useful Improvements in Safety-Pins, of which the following is a specification.

My invention is an improvement in safety pins, and has for its object to provide a pin of the character specified, wherein means is provided for locking the pin to the shield or clasp when the pin is closed, to prevent displacement of the point of the pin from the shield by strain upon the pin.

In the drawings:

Figure 1 is a perspective view of the improved pin;

Fig. 2 is a side view of the shield, with parts in section;

Figs. 3 and 4 are sections on the lines 3—3 and 4—4, respectively, of Fig. 2, each view looking in the direction of the arrows adjacent to the line.

In the present embodiment of the invention the improved pin comprises a pair of arms 1 and 2, which are connected by an integral coil 3 forming the spring which acts normally to force the free ends of the arms away from each other. One of the arms is pointed, as indicated at 4, and this arm is the movable arm of the pin.

A shield or clasp 5 is connected with the arm 1, the said shield or clasp being of sheet metal of suitable weight. This shield or clasp is substantially U-shaped, consisting of a body 5 and arms 6 and 7, and each of the arms 6 and 7 is substantially channel shaped, as is also the body 5, the channels of the arms and body being continuous and facing inwardly. The arm 6 receives within its channel the outer end of the arm 1, and the said arm is secured to the shield in any suitable manner, as, for instance, by brazing or soldering or the like. The other portion 7 is adapted to receive the point of the arm 2, and the said portion 7 has an upstanding tongue 8 at approximately the center, that is, midway between the side walls, which is adapted to extend through a slot 9 in the point of the pin.

This tongue extends to near the top of the side walls of the channel, and it will be noticed that the side walls of the channel 55 of the portion 6 have downward extensions

10 at about the location of the tongue 8, which serves to guide the point of the pin into the channel of the portion 7. The side walls of the channel of the portion 7 have guide extensions 11 at the outer sides of the 60 extensions 10 for guiding the point of the pin into the channel and into such position that the tongue will engage the slot. As shown, this tongue 8 is formed by striking up a portion of one wall of the channel, that 65 is, the tongue is cut out of the said wall and is bent inwardly midway between the walls, for the purpose specified.

It will be noticed that the sheath has a substantially channel shaped portion held in 70 spaced relation to the arm to which the sheath is secured and with the channel facing the said arm and that the sheath has an extension from the arm to which it is secured, extending between the side walls of 75 the channel shaped portion of the sheath, and that each of the side walls of the channel shaped portion has an inturned portion at its free edge. The distance between the extension and the inturned portion of each 80 side wall is equal to the distance between the inturned portions at the point where the pointed arm enters, so that the pointed arm is certainly guided into engagement with the tongue, without any possibility of the 85 pointed arm slipping between the tongue and the side walls.

I claim:

A safety pin comprising a pair of arms, one of said arms carrying a sheath and the 90 other being the piercing arm, said arm having a slot, and the sheath a tongue for engagement by the slot when the piercing arm is in the sheath, said sheath having a substantially channel shaped portion held in 95 spaced relation to the arm to which the sheath is secured and with the channel facing the said arm and having an extension from the said arm extending between the side walls of the channel shaped portion of 100 the sheath, each side wall having its upper edge inturned the distance between the extension and the inturned edge of each side wall being equal to the distance between the inturned portions and a tongue in the channel 105 between the side walls for engaging the slot, said tongue being struck up from the material of one of the side walls.

JOHN HENRY RICHARDSON.
